UNITED STATES PATENT OFFICE.

NORMAN W. BINGHAM, OF SOMERVILLE, MASSACHUSETTS.

HEEL-ATTACHING MACHINE.

SPECIFICATION forming part of Letters Patent No. 460,175, dated September 29, 1891.

Application filed March 6, 1891. Serial No. 383,958. (No model.)

To all whom it may concern:

Be it known that I, NORMAN W. BINGHAM, of Somerville, county of Middlesex, State of Massachusetts, have invented an Improvement in Heel-Attaching Machines, of which the following description, in connection with the accompanying drawings, is a specification, like letters on the drawings representing like parts.

10 The machine herein to be described is adapted to drive staples from the interior of the shoe outwardly into the heel to secure the latter in place and at the same time to drive slugs or nails into the tread of the heel.

15 The machine to be herein described is an improvement on that represented in United States Patent No. 315,675, to which reference may be had.

In this present invention the means employed to drive the staples into the heel are simplified and made stronger and more durable than in the said patent.

One part of my invention comprehends a machine containing a staple-holding box over 25 which the boot or shoe to be heeled may be placed, a series of drivers therein, a nail or slug box to bear against the tread end of the heel, and drivers therein, and means to actuate the said drivers, whereby the staples and 30 the nails or slugs are driven simultaneously into the heel from opposite directions.

Other features of this invention will be hereinafter described, and stated in the claims at the end of this specification.

35 Figure 1, in front elevation, represents a heel-ing-machine embodying my invention, the head and parts in it being in section; Fig. 2, a side view thereof partially broken out; Fig. 3, an enlarged sectional and broken 40 tail of the staple and nail boxes and the parts contained within them; Fig. 4, an upper side view of the nail or slug driver plate and nail-box; Fig. 5, an under side view of the nail or slug box shown in Fig. 4; Fig. 6, a right-hand 45 end view of the nail or slug box; Fig. 7, a top or plan view of the staple-box over which the boot or shoe is placed, the heel-seat plate forming the top of the staple-box being broken out.

50 The base or frame A has suitable bearings to sustain a power-shaft A', provided with a balance-wheel A², fast and loose pulleys A³

A⁴, and a pinion A⁵, as shown by dotted lines. This pinion engages a toothed gear B, fast on the main shaft B', having a crank-pin B², embraced by the strap of a connecting-rod B³. 55

The base has erected upon it two uprights or rods C C, the upper ends of which, reduced or shouldered, are extended through a head C' and have screwed upon them suitable nuts C² to thus confine the head in position. The head, as best shown in section, Fig. 1, receives a shouldered sleeve c, on which preferably rests a washer c', against which bears the lower end of a strong spring c², the upper end 65 of the said spring, as represented, receiving upon it a washer c³, which in turn is acted upon by suitable adjusting screws or devices c⁴, the said spring being of great force, so as to yield in case of excessive crushing strain, it having 70 no function to perform as a spring, but merely acting as a stop to prevent upward movement of the sleeve during ordinary work. The sleeve c at its inner side is threaded to receive a hollow spindle d. The lower end of 75 the sleeve c has fastened upon it a suitable hand-wheel c', (see Fig. 1,) rotation of the hand-wheel causing the threads of the sleeve acting upon the threads of the hollow shaft d to raise and lower the same. The lower end of 80 the sleeve d has screwed upon it a block d', having at its under side a dovetailed groove to receive a dovetailed projection e of a driver-plate e'. (Shown best in Figs. 1, 3, and 4.)

The driver-plate provided with a series of 85 usual drivers e² is provided centrally with a hole to receive a bolt e³ which is screwed into a nail or slug box f, provided with suitable holes, as f' (see Fig. 5) for the reception of nails or slugs f². Between the driver-plate 90 and the nail or slug box the bolt e³ is surrounded with a stiff spiral spring e⁴. The hollow spindle d receives within it a rod n, the lower end of which bears on the head of the bolt e³, the said rod having a collar n', on 95 which rests a spiral spring n³, the upper end of the spring abutting against a shoulder of the hollow sleeve, the spring n³ assisting the rod n, acting on the bolt e³, to keep the nail-box separated from the driver-plate e'. The 100 nuts n² on the rod prevent it from dropping out from the spindle when the plate e' is removed.

The front end of the nail or slug box f has

attached to it a breast-gage f^4 , while at its rear side the said box has attached to it by a screw f^6 a spring dog or holder f^7 , which engages the rear side of the heel, the breast of which is placed against the breast-gage. The breast-gage f^4 is provided with two lips or corner-gages f^8 . Normally the lower ends of the drivers e^2 stand in the holes f^1 .

The uprights or rods C act as guides for a reciprocating cross-head D , to which the connecting-rod B^3 is jointed. This cross-head D is represented as provided with an extension D' , having a dovetailed groove to receive the correspondingly-shaped foot of a post D^2 . The cross-head has an adjusting or stop screw o , the rotation of which out and in in an ear o' determines the position to be occupied by the post, the cross-head also having a locking device r , shown as a cam-lever, pivoted at 10, and having an eccentric or cam-shaped end to engage the foot of the post and hold it in adjusted position during the driving operation. The post is hollow and receives the shank of the staple-driver plate g , which shank is attached to the post by suitable bolts or screws.

The staple-driver plate carries a series of staple-drivers g' , having their upper ends cut away to leave oblong heads g^2 , the ends of the said heads entering guiding-grooves g^x in the staple-box g^3 , the heads of the staples s resting upon the heads of the drivers, as represented in Fig. 3. The staple-box g^3 has a shank g^4 , which is extended down through the hollow shank of the staple-driver plate, the said shank entering a spring g^5 , which is supported within the hollow post, the upper end of the spring g^5 receiving against it an adjustable collar g^6 , attached to the said shank, the spring g^5 normally acting to keep the staple-box elevated sufficiently above the staple-driver plate to withdraw the staple-drivers sufficiently into the staple-box to receive the heads of the staples and let the latter stand with their points in the slots m of the heel-seat plate m' , which acts as the top for the staple-box. The holes in the heel-seat plate are oblong, and the heads of the staple-drivers as they act to drive the staples into the heel come up into the said holes and fit them substantially snugly.

In practice the nails or slugs f^2 will be loaded into the nail or slug plate while the latter is off the machine and overturned from the position Fig. 3. The nail-box having been filled with nails or slugs and staples having been put into the staple-box, the operator will place the shoe to be heeled over the staple-box and post and will place the tread end of the heel with its breast against the breast-gage, making the dog f^7 engage the rear end of the tread-lift. With the heel applied to the nail-box, as stated, the operator will insert the dovetailed projection e into the dovetailed guide of the head or plate attached to the block referred to. Now the machine will be started, caus-

ing the rotating of the main shaft, so that it elevates the reciprocating cross-head, and in so doing the heel is at first firmly compressed between the staple-box and the nail-box, and in the further upward movement of the cross-head D the staple-drivers act to force the staples through the usual inner sole and outer sole and into the heel from its seat end substantially to its tread, and during the latter part of the movement of the staple-drivers the nail-box rises about the stationary drivers, compressing the spring e^4 , the drivers e^2 acting upon the nails or slugs f and driving them from the nail-box into the tread of the heel and through the tread partially into the heel.

I claim—

1. In a machine for attaching heels to boots or shoes, the following instrumentalities, viz: a support for the shoe to be heeled, a head C' , a hollow rotatable internally-threaded sleeve c therein, a hollow vertically-adjustable spindle contained in the said sleeve, a connected slug-driver plate, a series of slug-drivers, a slug-box, a bolt e^3 , a spring located between the plate and box to keep the box separated from the driver-plate to thus retract the drivers and leave place for the slugs, a staple-containing box having slots to receive staples and provided with a seat-plate, and a series of staple-drivers contained in the said staple-box, the combination being and operating substantially as described.

2. In a machine for attaching heels to boots or shoes, the following instrumentalities, viz: a staple-containing box having slots to receive staples, a seat-plate thereon, a series of staple-drivers, a staple-driver plate, a nail or slug box, a depending breast-gage and corner gages movable in unison with the said nail or slug box, a series of nail or slug drivers, and means to actuate the said parts, substantially as described.

3. In a machine for attaching heels to boots or shoes, the combination, with a nail or slug box having a depending breast-gage and corner gages, of an independent spring-catch attached to the rear side of the said nail or slug box and adapted to engage the rear part of the heel to suspend it from the under side of the nail-box, substantially as described.

4. The combination, in a heel-nailing machine, of a support for a shoe to be heeled, a head, a hollow rotatable internally-threaded sleeve therein and a hollow spindle held vertically adjustable therein, a connected slug-driver plate, slug-drivers, a slug-box, a bolt e^3 , and a spring located between the plate and box to keep the box separated from the driver-plate to thus retract the drivers and leave place for the slugs, substantially as described.

5. The combination, in a heel-nailing machine, of a support for a shoe to be heeled, a head, a hollow sleeve therein, a connected slug-driver plate, slug-drivers, a slug-box, a bolt e^3 , a spring located below the plate and box to keep the latter separated from the

driver-plate and leave space for the slugs, and a spring c^2 and devices to adjust the said spring c^2 , substantially as described.

6. The combination, in a heel-nailing machine, of a support for a shoe to be heeled, a head, a hollow sleeve therein, a connected slug-driver plate, slug-drivers, a slug-box, a bolt e^3 , a spring located between the plate and box to keep the latter separated from the driver-plate to leave space for the slugs, a spring c^2 , acting on the sleeve, a rod within the said spindle, and a spring to depress it against the said bolt, substantially as described.

15 7. In a heeling-machine, a post provided at one end with a staple-driver plate, a series of

staple-drivers, a staple-box, and a rest upon which the opposite end of the post is made adjustable horizontally, combined with a slug-box, a slug-driver plate, slug-drivers, a hollow spindle carrying said driver-plates, a sleeve thereon, and a spring surrounding the said spindle and bearing on the said sleeve, to operate substantially as described.

In testimony whereof I have signed my name to this specification in the presence of two subscribing witnesses.
